T. J. FEGLEY ET AL

VALVE GRINDER

Filed Aug. 12, 1926

UNITED STATES PATENT OFFICE.

THOMAS J. FEGLY AND GEORGE O. LEOPOLD, OF PHILADELPHIA, PENNSYLVANIA,
ASSIGNEES TO NORTH BRO'S MFG CO., OF PHILADELPHIA, PENNSYLVANIA, A
CORPORATION OF PENNSYLVANIA.

VALVE GRINDER.

Application filed August 12, 1926. Serial No. 128,794.

One object of our invention is to make a valve-grinding tool which will be simple in construction and which can be readily operated by hand.

5 A further object of the invention is to so construct the valve-grinder that it will have a gradually progressive reciprocating movement.

In the accompanying drawing:

10 Fig. 1 is a sectional elevation of our improved valve-grinder, on the line 1—1, Fig. 2; Fig. 2 is a sectional view on the line 2—2, Fig. 1;

15 Fig. 3 is an enlarged sectional view on the line 3—3, Fig. 4;

Fig. 4 is a sectional view on the line 4—4, Fig. 3; and

Fig. 5 is a sectional plan view on the line 5—5, Fig. 1.

20 The frame 1 of the valve-grinding tool may be of any shape desired. In the present instance, the frame encloses the gearing and a cover-plate 2 is threaded and adapted to a threaded opening in the casing so as to make 25 a tight joint, and the interior of this frame is preferably filled with grease or other lubricant.

30 The cover-plate carries the bearing 11 for a shaft 10. The spindle 3 extends longitudinally through the frame and is adapted to bushings 4 and 5 in the frame. These bushings are detachable and can be removed with the spindle when necessary. At the outer end of the spindle is a chuck 6, to which a valve- 35 engaging tool may be secured.

35 The inner end of the spindle has an annular groove 7 directly above the bushing 4. A U-shaped key 8 is located in the groove and rests on the bushing. A ball-bearing 9 is located 40 between the lower bushing 5 and the chuck.

45 The driving-shaft 10 is at right angles to the spindle 3 and has a handle 12 at its outer end and a cam 13 at its inner end. Secured to the shaft back of the cam 13 is a bevel gear-wheel 14 which meshes with two bevel pinions 15 and 16 loose on the spindle.

50 Each pinion has a number of key-slots 17 in its hub, into which is projected a key 18 shown clearly in Fig. 3. The key 18 is located in a longitudinal slot 19 in the spindle 3. Loose on the spindle 3 is a spool 20, having a flange 21 at each end forming an annular groove for the cam 13 of the shaft 10, so that when the

shaft is rotated, the spool is reciprocated freely on the spindle.

55 The key 18 has two projections 22. One projection is at one end of the spool and the other projection is at the opposite end of the spool. As the spool is reciprocated, the key is moved longitudinally in its slot.

60 Each end of the key is beveled and rides under bars 23 and 24 which extend across the slot 19 as shown clearly in Fig. 3. Located in pockets in the slot 19 are coil-springs 28, which yieldingly force one end of the key out of the slot when not controlled by a cross-bar. The cross-bar 24 is located nearer the centre of the shaft 10 than the other cross-bar, so as to hold the end 26 of the key in one of the key-slots in the pinion 15 a greater length of time 70 than the opposite end of the key is held in the pinion 16. This causes the spindle to have a progressive forward feed as well as a reciprocating movement, so that the valve will not grind at one place but will be gradually 75 turned as it is reciprocated.

Enclosing the upper bearing 4 and the inner end of the spindle is a suitably shaped hand-hold 27.

80 As the handle 12 is turned, the gear-wheel 14 turns the pinions 15 and 16 in opposite directions, and the cam 13 reciprocates the spool and controls the movement of the key 18, which first engages one pinion and then the other pinion, causing the reciprocation of the spindle 3, and as the key dwells a greater length of time in the hub of one pinion than in the other pinion, the spindle is moved forward at each reciprocation, so that the grinding action is distributed.

85 The above-described tool is compact and substantial and can be readily operated.

90 We claim:

1. The combination in a valve-grinder, of a frame having bearings; a spindle and a shaft mounted in the bearings, the shaft being at right angles to the spindle; two bevel pinions loose on the spindle; a flanged spool loose on the spindle and located between the two bevel pinions; a bevel gear on the shaft 100 meshing with the pinions; a cam on the shaft engaging and reciprocating the spool as the shaft is turned; a longitudinally movable key located in the spindle and moved longitudinally by the spool, the pinions having internal key-slots; and means for projecting the 105

key to engage one or the other of the pinions, one end of the key having a longer dwell in its hub than the other key so that the spindle will be moved progressively forward as it is reciprocated.

2. The combination in a valve-grinder, of a frame having a casing; a spindle extending through the casing; pinions on the spindle; a spool loosely mounted on the spindle; a detachable cap plate having a bearing; a shaft mounted in the bearing and having a gear-wheel thereon meshing with the pinions; a cam on the shaft engaging the spool; a pawl actuated by the spool arranged to engage one or the other of the pinions, said pawl having extensions with beveled ends; cross-bars on the spindle under which the pawl extends; and a spring tending to force the pawl in engagement with the pinions, one cross-bar being nearer the centre of the cam-shaft than the other cross-bar, so as to hold the pawl in engagement with one pinion for a greater length of time than with the other pinion, to cause the spindle to have a progressive reciprocating movement.

3. The combination in a valve-grinder, of a frame having a casing; a spindle extend-

ing through the casing; pinions on the spindle; a spool loosely mounted on the spindle; a detachable cap plate having a bearing; a shaft mounted in the bearing and having a gear-wheel thereon meshing with the pinions; a cam on the shaft engaging the spool; a pawl actuated by the spool arranged to engage one or the other of the pinions, said pawl having extensions with beveled ends; cross-bars on the spindle under which the pawl extends; and a spring tending to force the pawl in engagement with the pinions, one cross-bar being nearer the centre of the cam-shaft than the other cross-bar, so as to hold the pawl in engagement with one pinion for a greater length of time than with the other pinion, to cause the spindle to have a progressive reciprocating movement.

THOMAS J. FEGLEY.
GEORGE O. LEOPOLD.
